UNITED STATES PATENT OFFICE.

WILLIAM DALE WINDERS, OF COLUMBUS, OHIO.

LOOSE-LEAF BINDER.

Application filed October 12, 1926. Serial No. 141,182.

This invention relates to improvements in loose leaf binders and has for its principal object the provision of a simple and novel form of binder consisting of a pair of spaced parallel binding heads together with an improved means for controlling the spacing between said heads and the clamping action exerted thereby on a body of leaves arranged between the heads.

10 In many previous types of binders of this character it has been customary to provide binding posts between the heads operated by a key controlled mechanism for causing relative movement between said heads to 15 clamp and release the body of leaves therebetween. Due to the fact that these devices depend upon the use of a separate key to effect their operations and considerable objection has been advanced respecting the 20 same for the reason that the operating key is apt to become lost or misplaced and consequently difficulty is encountered in controlling the operation of the binding mechanism. It is therefore an outstanding object 25 of the present invention to provide a loose leaf binder wherein the operating mechanism is entirely self contained and especially, wherein the use of key operated mechanism is eliminated.

30 Another object of the invention resides in the provision of a loose leaf binder wherein the binding posts are formed to include a plurality of separable threadedly connected sections which may be added or subtracted as desired so as to regulate quickly and effectively the length of the post members so as to vary widely the distances between the binding heads to accommodate a larger or smaller number of leaf sections.

40 A further object of the invention resides in the provision of a loose leaf binder wherein one of the binding heads is provided with a pair of pivoted clamping devices, which when swung to assume active positions lie 45 within the confines of the binding head with which they are connected and operate to exercise a frictional pressure on the body of leaves between said heads so as to retain said leaves in securely bound relationship 50 with the heads.

With these and other objects in view, as will appear as the description proceeds, the invention consists in the novel features of construction, combinations of elements and 55 arrangements of parts hereinafter to be fully described and claimed.

In the accompanying drawing:

Figure 1 is a vertical longitudinal sectional view taken through the loose leaf binder comprising the present invention, the 60 plane of the section being longitudinal through the binding heads and associated parts,

Figure 2 is a similar view showing the heads in their separated positions, 65

Figure 3 is a vertical sectional view on the line 3—3 of Figure 1,

Figure 4 is a similar view on the line 4—4 of Figure 1,

Figure 5 is a plan view of one of the binding heads.

Referring more particularly to the drawings the numeral 1 designates the upper binding head of my improved binder, and the numeral 2 the lower binding head. It 75 will be understood that the terms upper and lower are used merely for convenience as it will be obvious that the respective heads 1 and 2 may be reversed in the order described if desired. Each head is formed preferably 80 from sheet metal and is of hollow interior construction. The lower head 2 is provided with a pair of longitudinally spaced openings 3, reinforced by means of inner tubular sections 4. Within the openings 3 there are 85 positioned a pair of binding posts 5.

Each of the posts 5 consists of a plurality of sections 6, comprising solid cylindrical bodies formed at one end with a threaded extension 7 of reduced diameter arranged 90 to be received within a correspondingly threaded socket 8 provided in the complementary end of the adjoining post section. It will be understood that any number of the sections 6 may be employed so as to regulate 95 the length of the sections as desired, and this is determined ordinarily by the number of leaves 9 clamped between the heads 1 and 2. The lower of the sections 6 receive head retaining screws 10 by which 100 upward movement of the post sections through the openings 3 is prevented. When assembled the post sections present a cylindrical body having a smooth exterior surface and of uniform diameter, which enable 105 said sections to pass through the openings 11 provided therefor in the leaves 9, without tearing, mutilating or injuring the leaves at this point.

The upper binding head 1 is provided inferiorly with a pair of plates 12 for each binding post. These plates are provided

with aligned openings for the reception of trunnions 13 provided upon a pair of clamping levers 14, which are movable through slots 15, provided in the head 1, into engagement with a longitudinally extending clamp-
5 ing bar 16, arranged between the heads 1 and 2 and extending parallelly therewith.

The bar 16 is carried normally by the head 1 and has its ends provided with vertical pins 17 arranged to pass through openings 18, formed in the head 1 and are provided interiorly with fixed collars 19 with which are engaged the upper ends of coil springs 20, the lower ends of the latter en-
10 gaging with the bottom wall of the head 1. It will be observed that the action of the springs 20 is normally to elevate the bar 16, as shown in Figure 2, so that the latter will lie along side of the inner wall of the head 1.

The upper sections 21 of the posts 5 are bifurcated as at 22 and pivotally receive, as at 23, the inner ends of a pair of operating handles 24, which extend laterally through openings 25 provided in the levers 14. When actively positioned the handles 24 lie within the confines of the upper binding head 1, but when inactively positioned, the said handles are capable of extending through elongated slots 26 provided in the outer wall of the head 1, as shown in Figure 2. By the medium of the slots 26 the handles 24 are conveniently accessible.

In operation, it will be seen that when the parts of the binder are positioned as disclosed in Figure 2, and it is desired to clamp the leaves 9 firmly in place, the upper binding head is lowered so that the bar 16 will be positioned upon the upper surface of the leaves 9. The vertically disposed handles 24 are then grasped at the outer ends thereof and are oscillated inwardly moving about the pivots 23. This causes corresponding rotation on the part of the levers 14 about their trunnions 13, which are then in registration with the pivots 23, as shown in Figure 3. The swinging of the handles 24 inwardly and downwardly, therefore, rocks the levers 14 and causes the ends of the latter to engage the bar 16 so as to force the latter downwardly upon the leaves 9 and to elevate the binding head 1 against the influence of the springs 20. This operation is continued until the levers 14 have been
55 swung to a position past the vertical plane

of the pivots 23, or in other words, until an off center position has been obtained. The influence then of the springs 20 is to hold the levers 14 and the handles 24 in locked active position, wherein a considerable frictional pressure is exercised on said leaves and an accidental release of the operating means is precluded. To separate the heads the reverse of the above described operation takes place, wherein the handles 24 are 65 swung upwardly instead of downwardly.

What is claimed is:

1. In a loose leaf binder, a pair of spaced parallel binding heads, a binding post arising from one of said heads, a lever element 70 pivotally carried by the other of said heads, a spring pressed bar carried by said last named head and engaged by said lever element, and an operating handle pivoted to the upper end of said binding post and arranged upon oscillation to rock said lever element.

2. In a loose leaf binder, a pair of spaced parallel binding heads, binding posts extending upwardly from one of said heads, 80 operating handles pivotally connected with the upper ends of said binding posts, and a pair of pivoted clamping elements carried by the upper of said heads and adapted to be rocked by the movements of said handles.

3. In a loose leaf binder, a pair of spaced parallel binding heads, binding posts arising from said heads, pivoted handles carried by the upper ends of said binding posts, and locking elements pivotally carried by the upper of said binding heads and provided with laterally arranged openings through which said handles extend, whereby oscillatory movement of said handles is 90 imparted to said locking elements.

4. In a loose leaf binder, a pair of spaced longitudinally extending parallel binding heads, binding posts arising from one of said heads, actuating handles pivoted to the upper ends of said posts, a pair of locking elements pivoted to the upper of said binding heads and connected with said handles to oscillate in unison therewith, and a spring mounted clamping bar carried by the upper 100 of said binding heads and movable in unison with said locking elements.

In testimony whereof I affix my signature.

WILLIAM DALE WINDERS.
